E. G. GARTIN.
CONTROL MECHANISM.
APPLICATION FILED JAN. 3, 1920.

1,363,203.

Patented Dec. 21, 1920.

UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

CONTROL MECHANISM.

1,363,203.

Specification of Letters Patent. Patented Dec. 21, 1920.

Application filed January 3, 1920. Serial No. 349,346.

To all whom it may concern:

Be it known that I, ELMER G. GARTIN, a citizen of the United States, residing at Claremont, in the county of Sullivan and 5 State of New Hampshire, have invented certain new and useful Improvements in Control Mechanism, of which the following is a full, clear, and exact specification.

My invention relates to control mechanism.

It has for its object to provide an improved feed controlling mechanism and one especially adapted to use on percussive tools of the fluid pressure fed type, such, for example, as stopers, and, more particularly to provide an improved braking mechanism for controlling the rapidity of feed of such devices. A further object of my invention is to provide a controlling mechanism which 20 is quick in operation, and in which a relatively small movement of the control mechanism causes a relatively great movement of the brake.

In the drawings, for purposes of illustration, I have shown one form which my invention may assume in practice.

In these drawings,—

Figure 1 is a side elevation of a pneumatically fed tool, the rear end of the feed cylinder and a portion of the piston rod being broken away.

Fig. 2 is a section of my improved feed controlling mechanism on the line 2—2 of Fig. 3.

Fig. 3 is a transverse section through the controlling mechanism housing on line 3—3 of Fig. 2 with the control mechanism shown in elevation, and parts broken away to show structural details.

Fig. 4 is a transverse section showing a structural detail on the line 4—4 of Fig. 3.

In this illustrative disclosure of my invention, a base 1 is provided having adjustably secured thereto the feed cylinder 2 of a usual form of pneumatic drill 3, the feed of the drill 3 being effected by movement of the piston 4 and of the piston rod 5 of the feed cylinder, and the feed being controlled by supply and exhaust of pressure fluid in a well-known manner through ports 6 and 7 extending through the piston rod, and by the coöperation of improved feed controlling mechanism hereinafter described.

Arranged on the forward end of the feed cylinder I have provided an enlarged hous-

ing 10 in which is located the feed control mechanism. Within the housing 10 is formed a chamber 11 through which the piston rod is normally freely slideable. Around the periphery of the piston rod and held in fixed relation by the housing is a collar of brake material 12 mounted in an elastic split metal housing 13. For the purpose of applying and permitting release of this brake, there is provided a resilient 60 spirally coiled spring member 14 having one end thereof held in fixed relation to the housing by a projecting lug 15 and having the other end thereof provided with a radially bent end engaged in a socket 16 65 formed in a worm wheel 17. The worm wheel 17 is mounted in such manner as to be freely rotatable in the housing 10 but is fixed against movement in the direction of motion of the piston. In order to provide 70 a freely rotatable bearing for the worm wheel, the lateral portions of its periphery are smooth, but the central portion of its periphery is provided with suitable teeth 18 to coöperate with the teeth formed upon a 75 worm 19. The worm 19 is suitably journaled in a transverse enlargement 21 of the housing 10, being formed upon a shaft 22, and a spring 23 is interposed between the worm and the inner end of the housing 21 80 and surrounds the shaft. A hand wheel 24 is secured to the opposite end of the shaft 22. The structure so far described is of well-known commercial construction and no 85 claim is made to it *per se*.

Owing to the worm and wheel construction and the length of the spiral spring tensioning member, a considerable rotation of the hand wheel 24 secured to the shaft 22 would be necessary to effect tightening or 90 loosening of the brake material 12. As I have found that in some cases it is desirable to permit a rapid adjustment of the tension of the brake upon the piston rod, I have devised the improvement consisting of 95 cluching, as at 27, to the hand wheel 24 a collar 25 which has a threaded engagement with an opening 26 formed in the end of the transverse housing 21. The worm teeth 19 are formed with a left hand thread so that 100 by imparting a right hand turn to the shaft 22, the worm wheel in Fig. 3 will be caused to turn in the direction of the arrow, or clockwise. By providing a right hand thread connection between the parts 25 and 110

26, it will be obvious that a right hand turn of shaft 22 will cause the worm 19 to be bodily moved to the right in Fig. 3 which will likewise cause an additional movement 5 of the worm wheel in the direction of the arrow in this figure. It will thus be seen that I have provided a device for increasing the rapidity of motion of the worm wheel 17 and accordingly that I have provided a 10 more rapid method of adjustment for the tension adjusting member 14.

While I have shown and described only a single thread construction, it will be obvious that double or even triple threads 15 might be readily used with a resultant greater rapidity of adjustment than in the device which I have illustrated. The great advantage of my construction is that by the arrangement of the parts as illustrated, 20 twice the speed of adjustment can be obtained without change in the pitch of either of the screws, assuming that the pitch of the screw and of the worm is the same, and accordingly the tendency to slip will be no 25 greater than were my second screw connection omitted. It will also be evident that, if desired, the pitch and the threads of either of the screws embodied in my device may be varied to obtain any combination of motion 30 desired.

While I have in this application specifically described one form which my invention may assume in practice, it will be understood that this form of the same is 35 shown for purposes of illustration and that the invention may be modified and embodied in other forms without departing from its spirit or the scope of the appended claims.

40 What I claim as new and desire to secure by Letters Patent is:

1. In a control mechanism, a longitudinally movable member, a rotatable member, a braking member coöperating with the 45 former and having one end thereof fixed and the other end thereof secured to said rotatable member and adapted to be tightened or slackened by rotation of said member, gearing adapted to rotate said member, 50 and means for causing simultaneous rotative and rectilinear movement of one element of said gearing.

2. In a control mechanism, a longitudinally movable member, a worm wheel relative to which said longitudinally movable member is movable, a braking element surrounding said member and having one end thereof fixed and the other end thereof secured to said worm wheel, a worm to rotate 55 said wheel, a fixed nut, and a screw coöperating with said worm and said fixed nut

to rotate said wheel through simultaneous rotative and longitudinal movement of the worm.

3. The combination with a longitudinally 65 movable member, a toothed rotatable member, a braking element coöperating with said longitudinally movable member and having one end thereof fixed and the other end thereof secured to said rotatable member 70 and adapted to be tightened or slackened by rotation thereof, and a toothed driving member engaging said toothed rotatable member, of means to cause rotative movement of the teeth of said toothed driving member and a 75 simultaneous movement of said teeth in a direction tangential to the toothed rotatable member.

4. The combination with a gear, of two telescopically arranged members and a helical member coiled about one of said telescopically arranged members and having one portion fixed as to circumferential movement and another portion thereof secured to said gear, said gear being coaxially disposed 80 with respect to said last mentioned telescopically arranged member, together with a worm to rotate said gear, and a screw coaxially arranged with respect to said worm and adapted to move it longitudinally and 85 rotate it simultaneously.

5. The combination with a gear, of two telescopically arranged members and a helical member coiled about one of said telescopically arranged members and having 95 one portion fixed as to circumferential movement and another portion thereof secured to said gear, said gear being coaxially disposed with respect to said last mentioned telescopically arranged member, together 100 with a worm to rotate said gear, and a screw coaxially arranged with respect to said worm and adapted to move it longitudinally and rotate it simultaneously, the rotative effect of said worm and said screw on said 105 gear being additive.

6. The combination with two telescopically arranged members, a worm wheel rotatively arranged around one of said members, a helical member coiled about the said 110 member having one portion thereof fixed and another portion thereof secured to said worm wheel, a worm coöperating with said worm wheel, and a shaft upon which said worm is mounted, of a fixed nut, a screw engaging said fixed nut and secured to said shaft, and means for rotating said shaft to impart to said worm wheel the cumulative 115 effect of said worm and of said screw.

In testimony whereof I affix my signature. 120

ELMER G. GARTIN.
